THERMOSTAT VALVE MECHANISM

Frank H. Schoenfeld, Cleveland Heights, Ohio

Application May 27, 1935, Serial No. 23,787

11 Claims. (CL. 236—48)

This invention relates to a boiler, more particularly a fuel control valve, operated by a thermostat. My invention is shown applied to a water heater of the storage tank type having a burner utilizing a gaseous fuel as illustrating its preferred application.

One object of the invention is to provide an improved thermostatic, valve operating mechanism that is relatively simple and positive in operation.

Another object of the invention is to provide an improved thermostatic, valve operating mechanism having a multi-leverage mounted for adjustment relative to the thermostat elements, whereby the latter may be effective within a smaller or greater temperature range of the water in the tank.

Other objects of my invention will be understood from the following description of the preferred embodiment of my invention.

Referring to the drawings,

Fig. 1 is a vertical section of a water heater apparatus, having applied thereto a thermostat mechanism embodying my invention, the tank being shown in section.

Fig. 2 is a front elevation of the mechanism.

Fig. 3 is a view, partly in section, of the mechanism.

Figs. 4, 5, 6 and 7 are sections on the lines 4—4, 5—5, 6—6 and 1—7, respectively, of Fig. 3.

Fig. 8 is a view showing certain parts in perspective, disassembled.

Referring to Fig. 1, 1 indicates a suitable tank which is supplied with water by means of a supply pipe 2 connected with pressure supply mains. The tank 1 is shown mounted on a pedestal 3. The walls of the tank may be insulated in any desired manner.

4 indicates a suitable heating device preferably disposed at one side of the tank 1 and comprising an encased coil 5 and a gaseous fuel burner 6, supplied with fuel through a pipe 7. The lower end of the coil 5 is connected by a pipe 8 with the lower portion of the tank, whereas the upper end of the coil 5 is connected by a pipe 9 to the top of the tank 1, whereby heating of the water in the coil induces a flow therethrough, the effect of which is to heat and maintain heated the water in the tank. 10 indicates a supply pipe leading from the upper portion of the tank 1 to convey the heated water to the station or stations for use, the pipe 10 being preferably connected to the pipe 9. As will be understood, when the hot water is drawn off through pipe 10, it is replaced by cold water supplied by pipe 2, the effect

of which is to lower the temperature of the body of water in the tank 1.

11 indicates generally a thermostatic mechanism mounted in the side wall of the tank 1 and interposed in the fuel pipe 7 to control the flow therethrough. Of the mechanism 11, 12 indicates a casting having a hollow boss 13. The boss is threaded interiorly to engage a nipple mounted in the container wall where the latter is encased with insulation or a jacket and is also threaded exteriorly to engage a nut 14, suitably secured to the side wall of the tank. The casting is also shaped to form a chamber 15 and an off-set portion 16. The wall of the casting at the lower end of the chamber 15 terminates in a threaded nipple 15 12a to which the lower portion of the pipe 7 is connected. The upper end of the chamber is closed by a removable cap 12' preferably engaging screw threads on the inner wall of the chamber. The wall of the casting between the boss 13 and chamber 15 is formed with a transverse opening 17 for a purpose later set forth and aligned openings 18, 18a, co-axial with the axis of the boss 13. 19 indicates a tube threaded at its inner end in a liquid tight manner into the opening 18a and provided at its outer end with a bushing 19a which is threaded internally. The tube 19 is formed of a material, such as copper, that has a high co-efficient of expansion. 20 indicates a rod within the tube 19 and having threaded engagement at its outer end with the bushing 19a so that by rotating the rod it may be adjusted endwise for a purpose later set forth. The inner end of the rod 20 slidably extends through the opening 18 into the chamber 15 for engagement with 30 a multiplying leverage, indicated as an entirety at 21, mounted within the chamber 15 and arranged to operate a valve 22. The rod 20 is formed of a suitable material, such as invar metal, which has a low co-efficient of expansion. The rod 20 is 35 supported centrally of the tube 19 by the bushing 19a and walls of the opening 18.

The offset portion 16 of the casting is constructed or shaped to form a chamber 23, which is in axial relation to an opening 24 formed in 45 the adjacent side wall of the chamber 15, and a lateral passage 25 communicating with the chamber 23. The wall of the opening 24 forms the seat of the valve 22. The inner wall of the passage 25 is threaded to permit connection 50 thereto of the fuel supply pipe 7. 26 indicates a hollow plug for closing the outer end of the chamber 23. The plug is closed at its outer end and serves as a mounting for the valve element 22' of the valve 22. The outer end portion of the 55

plug 26 is provided with external threads and removably screwed into the outer end of the chamber 23. The inner end of the plug 26 is closed by a cap 27 removably threaded therein. 5 The cap 27 is formed with a through, axially disposed opening in which is slidably mounted the shank 28 for the valve element 22'. The inner end of the shank 28 is engaged by an expansion spring 29 which is arranged within the plug 26 and normally tends to force the valve against its seat to close the opening 24. As will be understood, the gaseous fuel supplied by the pipe 7 flows through the passage 25, chamber 23, opening 24, chamber 15 to the portion of the pipe 10 7 connected to the burner when the valve 22 is actuated to open position by the leverage 21 under control of the thermostat elements. The valve element 22' is threaded on the shank 28 to permit of adjustment therealong the effect of 15 which is to increase or decrease the tension of the spring 29.

30 indicates a frame removably fitting within the chamber 15 and having sliding engagement with the inner walls thereof to permit its adjustment longitudinally of the chamber by a mechanism indicated as an entirety at 31. The frame 30 supports the leverage 21, so that when the frame is adjusted, the leverage is bodily moved relative to the rod 20, the result of which is to 35 change the effective length of the lever arm between the rod 20 and the fulcrum for that lever engaged thereby with a corresponding proportionate change in the effective length of the other arm of the lever. This adjustment serves 40 to increase or decrease the range of operation of the thermostat elements to open and close the valve 22. By preference, the thermo-elements and the leverage 21 are normally arranged to open the valve 22 when the temperature of the 45 water in the tank 1 drops to 168° F. and to close the valve 22 when the temperature of the water rises to 180° F., thereby providing a temperature range of 12° F. between closing and opening of the valve. By adjusting the frame 30 upwardly this temperature range may be decreased; by adjusting the frame in the reversed direction the range is increased. The frame 30 is shaped so 50 that spaced side portions thereof will engage guideways formed in the inner wall of the chamber 15. The inner wall of the chamber 15 is cylindrical and formed with longitudinally extending, substantially right-angled shaped grooves 15a, preferably broached by a suitable tool, such grooves forming the guide-ways for the 55 frame 30. The frame 30 is preferably formed of a section of sheet metal, which is stamped out and bent by suitable dies providing an intermediate wall 30a and side walls 30b, the wall 30a having at its lower end an inturned member 32 disposed between the side walls 30 of the frame to reinforce them. The member 32 terminates in an arm 33 which is bent upwardly for a purpose later set forth. The intermediate wall 30a of the frame 30 is formed with an upper opening 34 and 60 a lower opening 35, the purpose of which openings will later appear. Where portions of sheet metal are bent into an angular relation the corner assumes a slightly rounded shape as shown at 36 and accordingly if those portions of the frame 30 that enter and slide in the guide-ways 15a were of this shape the guide-ways would have to be broached deep enough to engage the frame walls beyond the rounded corners, but by forming 65 in the intermediate wall 30a or side walls 30b (preferably the latter) openings 37 adjacent the

corners, those portions of the corners co-extensive with the openings 37, as shown at 37a, assume a well defined right-angle shape, so that relatively slight broaching is required to form the guide-ways 15a. As will be understood from 70 Figs. 3 and 4, the free edges of the side walls 30b and corners 37a slide in the guide-ways 15a.

The upper ends of the side walls 30b are cut away to form shoulders 38, the resulting corners forming bearings for knife edge bearing or fulcrum elements 39 provided on the opposite sides of a lever 40, which constitutes one element of the leverage 21. The elements 39 are bent outwardly so that their knife edges may rest in their bearings and clear the adjacent walls. The fulcrum arrangement for the lever 40 provides a short arm 40a which is engaged by the inner end of the rod 20 and a long arm 40b which pivotally supports at its outer or lower end a second lever 41, (constituting the other element of the leverage 21), so as to move the pivot for the lever 41 to either side of the arm 33, as later set forth. The lever 40 is off-set at 40' to provide operating space for the lever 41 and is provided at its free end with in-turned legs 42 on which the lever 41 is pivoted, the legs 42 being spaced to accommodate the fixed arm 33 between them. The legs 42 are formed with alined V-grooves 42a to receive knife edges 43 provided on spaced legs 44 at the pivoted end of the lever 41, these legs being 30 spaced to accommodate the arm 33 and lower end of a tension spring 45 which is connected at one end to the arm. The lever 41 is off-set at 41a, 41b, opposite to the offset 40' of the lever 40 to accommodate the spring 45. The spring 45 is 35 connected at its other end to the outer end portion of the lever 41, as shown at 45a, and serves to swing its outer end, with a snap action movement, toward or from the valve element 22' upon movement of its pivoted end relative to the arm 40 40, that is, to either side of a plane cutting the arm 33 and connection 45a between the spring 45 and lever 41. The upper end of the lever 41 is provided with a lateral extension 46 the outer end portion of which is reduced to form shoulders 47. The outer end of the reduced portion terminates in a thrust member or striker 48, which engages with and operates the valve element 22' to open the valve 22; such end being preferably bent at an angle to form a relatively 50 wide surface for engaging the valve element 22' or the projecting end of its shank 28 in all adjusted positions of the leverage 21. As shown, the extension 46 and striker 48 operate in and through the opening 34. The upper end portion of the lever 41 is provided at its opposite sides with rearwardly extending lugs 41x which engage the lever 40 to limit the movement of the lever inwardly or away from the valve 22 under the influence of the spring 45, whereas the shoulders 47 engage the wall 30a of the frame 30 to limit the movement of the lever under the influence of the spring in the opposite direction. 55

48' indicates an arm fixed by a set screw 48a to the rod 20 substantially midway the side walls 60 of the opening 17. The arm 48' projects beyond the side wall of the casing 12, whereby it may be engaged and operated relative to graduations on the edge of a wall 49. Such operation of the arm 48' will rotate the rod 20, the effect of which 65 is to adjust the rod 20 endwise relative to the tube 19, due to its threaded connection with the bushing 19a. This adjustment moves the range 70 of movement of the operating mechanism 21 up or down. If the parts are set for a twelve degree 75

range, for example, from 168° to 180° F. the foregoing described adjustment will move the range, such as from 175° to 187° F.

For increasing or decreasing the range, for example from 175° to 180° F. I provide means for adjusting the effective length of the lever arm 40a, that is, the distance from the fulcrum of the lever 40 to the point of contact of the thermo-member or rod 19 with the lever arm 40a. This is preferably accomplished by bodily adjusting the operating mechanism 21, as already set forth. As the mechanism 21 is carried by the frame 30, movement of the latter upwardly or downwardly by the mechanism 31 will effect the adjustment last referred to. The mechanism 31 comprises the following: 50 indicates a hollow boss threaded into an opening 51' formed in the side wall of the casing 12 and forming a bearing for a shaft 52. The inner end of the shaft 52 is provided with the pinion 53 which meshes with a rack 54 provided on one side wall of the opening 35. The outer end of the shaft has fixed to it a cup member 55. The circumferential edge of the cup member 55 fits closely against the flange of the boss 51. 56 is a suitable gasket or packing surrounding the shaft 52 within the cup member 55 and compressed tightly against the boss flange by an expansion spring 57 to form a seal. As shown the spring 57 surrounds the outer portion 30 of the shaft 52 and engages the end wall of the cup member. The tension of the spring on the cup member 55 serves to normally prevent rotation thereof and accordingly prevents the shaft from rotating, except when such tension is overcome by sufficient force applied to the cup member 55. If desired the outer end of the shaft may be formed with a kerf and/or its side walls shaped to take a suitable tool when rotation of the shaft 52 is to be made. By rotating the shaft 40 52, the frame 30 may be raised or lowered along its guides 15a. The cap 12' closes the upper end of the chamber 15 and when it and the boss 51 are removed, the frame 30 and mechanism 21 may be removed from the chamber 15. The lever arm 40a is preferably provided with a groove 40a' to prevent lateral movement of the rod 20 relative to the lever.

It will be understood that to those skilled in the art to which my invention relates, many changes in construction and widely differing embodiments will suggest themselves without departing from the spirit and scope of the invention as set forth in the appended claims, the disclosures and the description herein being purely illustrative and not intended to be limiting.

What I claim is:

1. In a device of the class described, the combination of a casing shaped to form a chamber and having an outlet opening and an inlet opening, a normally closed, spring operated valve for one of said openings, a support within said chamber, guide means between said support and the inner wall of said chamber for adjustably supporting said support therein, a multiple leverage mounted in said support, one lever of said leverage being arranged to operate said valve, a thermo-element arranged to engage another lever of said leverage to operate the latter, and means for adjusting said support.

2. In a device of the class described, the combination of a casing shaped to form a chamber and having an outlet opening and an inlet opening, a normally closed, spring operated valve for one of said openings, a support within said

chamber, guide means between said support and the inner wall of said chamber for adjustably supporting said support therein, a multiple leverage mounted in said support, one lever of said leverage being arranged to operate said valve, a thermo-element arranged to engage another lever of said leverage to operate the latter, and means for adjusting said support, said adjusting means including an element extending through the wall of the casing to permit adjustment of 10 said support.

3. In a device of the class described, the combination of a casing shaped to form a chamber and having an outlet opening and an inlet opening, a normally closed, spring operated valve for 15 one of said openings, a support within said chamber, guide means between said support and the inner wall of said chamber for adjustably supporting said support therein, a multiple leverage mounted in said support, one lever of 20 said leverage being arranged to operate said valve, a thermo-element arranged to engage another lever of said leverage to operate the latter, and means for adjusting said support, said adjusting means comprising a rack on said support, a pinion in mesh therewith and a shaft fixed to said pinion and extending through the wall of said casing, whereby the pinion may be operated.

4. In a device of the class described, the combination of a casing shaped to form a chamber open at one end and having an inlet opening and an outlet opening, a normally closed, spring operated valve for one of said openings, a support 35 slidably engaging the wall of said chamber for adjustment thereon and removable therefrom through the open end thereof, a removable cap for said opening, a thermo-element, a multiple leverage operatively related to said thermo-element and said valve and carried by 40 said support for bodily movement therewith, and means for adjusting said support, said means including an element operable exteriorly of said casing and removably mounted in the wall thereof.

5. In a device of the class described, the combination of a casing shaped to form a chamber open at one end and having an inlet opening and an outlet opening, a normally closed spring operated valve for one of said openings, a support 50 slidably engaging the walls of said chamber for adjustment therein and removable therefrom through the open end thereof, a removable cap for said opening, a pair of thermo-elements one of which extends into said chamber, means for 55 adjusting the last mentioned element relative to the other element, a multiple leverage operatively related to said last mentioned thermo-element and said valve and carried by said support for bodily movement therewith, and means for adjusting said support to vary the relation of said thermo-element to said leverage.

6. In a device of the class described, the combination of a casing shaped to form a chamber and having inlet and outlet openings, a valve 65 for one of said openings, a thermo-element extending into said chamber, a support removably mounted in said chamber, a multiple leverage comprising a main lever fulcrumed on said support and arranged to be engaged by said thermo-element, a second lever pivoted on one end of said main lever, and a spring connected at one end to the outer end of said second lever and at its other end connected to said support substan- 70 75

tially midway the limits of movement of the axis of said second lever on said main lever.

7. In a device of the class described, the combination of a casing shaped to form a chamber and having inlet and outlet openings, a valve for one of said openings, a thermo-element extending into said chamber, a support removably mounted in said chamber, a multiple leverage comprising a main lever fulcrumed on said support and arranged to be engaged by said thermo-element, a second lever pivoted on one end of said main lever, and a spring connected at one end to the outer end of said second lever and at its other end connected to said support substantially midway the limits of movement of the axis of said second lever on said main lever, and means for limiting the movement of said second lever in opposite directions.

8. In a device of the class described, the combination of a casing shaped to form a chamber and having inlet and outlet openings, a valve for one of said openings, a thermo-element extending into said chamber, a support removably mounted in said chamber, a multiple lever comprising a main lever fulcrumed on said support and arranged to be engaged by said thermo-element, a second lever pivoted on one end of said main lever, and a spring connected at one end to the outer end of said second lever and at its other end connected to said support substantially midway the limits of movement of the axis of said second lever on said main lever, and means for limiting the movement of said second lever in opposite directions, and means for adjusting said support to vary the relation of said thermo-element to the fulcrum for said main lever.

9. In a device of the class described, the combination of a casing shaped to form a chamber and having inlet and outlet openings, a valve for one of said openings, a thermo-element extending into said chamber, a support removably mounted in said chamber, a multiple leverage comprising a main lever fulcrumed on said support and

arranged to be engaged by said thermo-element, a second lever pivoted on one end of said main lever, and a spring connected at one end to the outer end of said second lever and at its other end connected to said support substantially midway the limits of movement of the axis of said second lever on said main lever, and means for limiting the movement of said second lever in opposite directions, and means for adjusting said support to vary the relation of said thermo-element to the fulcrum for said main lever, the free end of said second lever having a long striker for engagement with said valve to compensate for the adjustment of said support.

10. In a valve of the character described, the combination of a casing having an inlet and an outlet opening and having broached parallel seats, a supporting member formed to be slidably mounted within said casing and fitted onto said seats, a plurality of levers within said member and comprising a main lever being pivoted to said member and another lever being pivoted to said main lever, a normally closed, spring-operated valve cooperating with one of said openings and adapted to be opened by the movement of said plurality of levers, and means for actuating said main lever.

11. In a valve of the character described, the combination of a casing having broached parallel seats, a frame slidably mounted within the casing and carried by said seats, means extending outside of the casing for effecting movement of the frame with respect to said casing, a plurality of levers mounted within said frame and comprising a main lever being pivoted to the frame, another of said levers being pivoted to said main lever, means for actuating said main lever, a spring for holding said levers onto their pivotal supports and for effecting a snap action, and a valve tending normally to seat and adapted to be held from its seat by the action of said plurality of levers.

FRANK H. SCHOENFELD.
